UNITED STATES PATENT OFFICE.

CLAUDE A. LEWIS, OF HOUSTON, TEXAS, ASSIGNOR TO AMERICAN WINDOW COMPANY, A CORPORATION OF DELAWARE.

WINDOW SUPPORT.

Application filed September 7, 1926. Serial No. 133,928.

My invention relates to windows, and particularly to windows in which the upper sash is adapted to be pivoted at its lower end so as to swing the upper end inwardly 5 for ventilation or to expose the outer face of the window sash.

It is an object of the invention to provide a support for the upper sash which will allow it to be swung inwardly at the upper 10 end and support the sash in the swinging movement and to allow the sash to be removed from its support when the position of the sash has been entirely reversed.

It is desired that the support be such as 15 to allow an easy swinging movement of the sash and to prevent any lateral or longitudinal movement of the sash while it is being moved.

It is also an object to provide a mounting 20 for a window sash which allows the lower sash to be raised and lowered within the casing and also permits the sash to be reversed in position so as to permit access to the outer side of the window pane.

Referring to the drawings in which all 25 non-pertinent parts have been omitted, Fig. 1 illustrates a side view of the upper sash mounted in accordance with my invention, the lower sash being shown on the line 1—1 30 of Fig. 4. Fig. 2 is a similar view with the upper sash moved inwardly from the position shown in Fig. 1. Fig. 3 is a detached view of the upper sash reversed. Fig. 4 is a transverse section through the casing and 35 the upper sash. Fig. 5 is a broken vertical section on the line 5—5 of Fig. 1. Fig. 6 is a broken perspective view illustrating the construction of the rider, upon which the lower sash is mounted. Like numerals of 40 reference are employed to designate like parts in all the views.

In the drawing, the lower sash 1 is indicated as being attached at its sides to riders 2. As shown in Fig. 6, the rider is made 45 up of a plate of sheet metal bent into approximately rectangular shape, one side 3 being opened to allow the sliding of the rider relative to the support for the upper sash. Adjacent the upper end of the rider 50 is a slot 4 formed on the inner side adjacent the sash and connecting at its upper end with an opening 5 in the forward side of

the rider. At the lower end of the rider is the vertical slot 6 closed at both ends and limiting the movement therein of a pin 7 55 upon the sash.

The window sash 1 has the laterally projecting pin 7 at its lower end to fit within the slot 6. At its upper end it has lateral projecting plates 8 secured on the sash and 60 extending to each side of the sash so as to project into the opening 5 when the sash is in raised position with the pin 7 at the upper end of the slot 6. The plate may then be moved inwardly and allowed to drop into 65 the slot 4 and the sash is lowered relative to the rider into the position shown in Figs. 1 and 2.

The upper sash has, at a point spaced slightly from the lower end, a plate 9 which 70 has a forwardly extending arm 10, the end of which is curved downwardly on the arc of a circle to form a hook 11 to receive a pin 12 upon a supporting bracket.

A plate 13 is secured to the casing 14 at a 75 point spaced slightly below the upper end of the lower sash. Its upper face 14 is adapted to support the lower side of the plate 9. At its forward end the plate 13 is formed with a bracket 15. As shown in 80 Fig. 5 the bracket 15 is made of sheet metal, the forward end being bent upwardly to form two walls spaced apart the proper distance to receive the hooked end 10 of the plate 9 upon the upper sash. The pin 12 is 85 supported on the two walls of the groove 16 formed by the bracket. Below the pin 12 the metal of the bracket is bent laterally and extended down at 17 to form a support for the upper sash. The forward hooked end 90 11 upon the upper sash fits within the space or groove between the walls of the bracket, as shown particularly in Fig. 5, and it will be noted that the close fit of the supporting plate of the upper sash within the bracket 95 15 allows no lateral movement whatever of the plate 10 or the sash connected therewith. It is understood that a plate 13 is formed at each side of the casing and arms upon the sash engage therein, as shown particularly 100 in Figs. 1 and 2. The support thus allows the upper sash to be swung inwardly until it is reversed in position, as shown in Fig. 3, and in that position it may be raised up-

wardly away from the pin 12 and removed from the casing.

The lower sash may be swung inwardly to expose the outer face by raising the sash relative to the rider 2 and bringing the plate 8 on the said sash into registration of the opening 5 after which the upper end may be swung inwardly, about the pivot formed by the pin 7. In this position the lower sash 10 may be entirely removed from the rider by tipping one side of the sash upwardly relative to the other so as to allow the pin 7 to be removed from the slot 6 in the rider and after that pin has been released the other 15 one may be also released without difficulty.

The advantages of this construction over previous forms of this type of window lie in the support for the upper sash upon a bracket on the casing entirely independent 20 of the lower sash and allowing the swinging movement of the upper sash without any lateral or longitudinal movement of the same during the swinging and which permits of the release of the sash when it has been reversed. The manner in which the lower sash is mounted upon its rider so that it may 25 be reversed or removed also has advantage over former types of mounting for windows now in use. The forming of the rider 2 in such manner as to allow its movement without interference from the arm 15 on the bracket 13 is also an element of value.

Having thus described my invention, what I claim as new and desire to protect by Letters Patent is:

1. In a window, upper and lower sashes, a rider for said lower sash, a pin at the lower end of said lower sash projecting into a slot in said rider, a laterally extending plate at 40 the upper end of said lower sash, said plate being adapted to be received in a slot in said

rider, whereby said sash may be released from said rider at its upper end in the manner described and said sash be then free to swing into reversed position. 45

2. In a window, a casing, upper and lower sash therein, said lower sash being vertically 50 slidable in said casing, a plate on said casing at the lower end of said upper sash, a pin on said plate and means on said sash pivotally connecting with said pin, to allow a swinging of said upper sash therein.

3. In a window, a casing, upper and lower sash therein, said lower sash being vertically 55 slidable in said casing, a plate on said casing at the lower end of said upper sash, a pin on said plate and means on said sash pivotally connecting with said pin, to allow a swinging of said upper sash therein, and means on said plate to prevent play of said 60 sash relative thereto.

4. In a window, a casing, upper and lower sashes therein, said lower sash being vertically 65 slidable, a plate on said casing adapted to support said upper sash and hold it normally from vertical movement, a pin on said plate supported inwardly from said upper sash, and a plate on said upper sash having rigid means thereon engaging said pin to allow a swinging of said upper sash thereon. 70

5. In a window, a casing, upper and lower sashes therein, said lower sash being vertically 75 slidable, a plate on said casing below said upper sash and means on said upper sash, engaging means on said plate to allow the said upper sash to swing inwardly to reversed position in front of said lower sash.

In testimony whereof I hereunto affix my signature this 2d day of September A. D. 80 1926.

CLAUDE A. LEWIS.
